CLAIM

The ornamental design for a vehicular running bar, as shown and described.

DESCRIPTION

FIG. 1 is a top plan view of a first embodiment of the vehicular running bar embodying my new design;

FIG. 2 is a top and front perspective view thereof;

FIG. 3 is a top, front, and left side perspective view thereof;

FIG. 4 is a top and left side perspective view thereof;

FIG. 5 is a top and rear perspective view thereof;

FIG. 6 is a top, rear and left side perspective view thereof;

FIG. 7 is a top, front, and right side perspective view thereof;

FIG. 8 is a bottom plan view thereof;

FIG. 9 is a top and front perspective view of a second embodiment of the vehicular running board embodying my new design;

FIG. 10 is a top and rear perspective view thereof;

FIG. 11 is a bottom plan view thereof;

FIG. 12 is a top and front perspective view of a third embodiment of the vehicular running board embodying my new design;

FIG. 13 is a top and rear perspective view thereof;

FIG. 14 is a bottom plan view thereof; and,

FIG. 15 is a left side elevation view of the first, second, and third embodiments of the vehicular running board, with the right side view being a mirror image thereof.

The broken lines in the drawings illustrate portions of the vehicular running bar that form no part of the claimed design.

1 Claim, 5 Drawing Sheets
